Inventor,

Charles F. Clapham,

By John Moore
Attorney

UNITED STATES PATENT OFFICE.

CHARLES F. CLAPHAM, OF NEWPORT NEWS, VIRGINIA.

HIGH-SPEED REDUCTION GEARING.

Application filed November 9, 1920. Serial No. 422,802.

To all whom it may concern:

Be it known that I, CHARLES F. CLAPHAM, a subject of the King of England, residing at Newport News, in the county 5 of Warwick and State of Virginia, have invented certain new and useful Improvements in High-Speed Reduction Gearing, of which the following is a specification.

This invention relates to high speed reduction gearing and has for its object the elimination of errors of alignment between the pinion and gear teeth due to wear of bearings, distortion of casing, errors of tooth cutting, which creep in even when 10 the most accurate gear cutting means are used or other causes, and the obtaining of even distribution of load on the teeth in contact over the whole face width. It is of great importance to avoid wear of teeth 15 due to differences in stresses in various portions of the teeth and the vibration which will be caused by uneven load distribution. In order to obtain the desired result, the reduction gear pinion is made in two separate 20 sections, each section forming a hollow sleeve with a coupling at its outer end by which it is attached to the flexible driving shaft which passes through both sleeves. Each section of the divided pinion 25 is mounted on an independent frame or bed, and the construction and mounting of these frames is such that it provides for the angular movement of each section of the pinion in a plane tangential to the pitch 30 circles of pinion and gear sections at the point of contact. The construction also provides for the longitudinal movement of pinion sections as a unit. The equality of 35 forces on each section of the divided pinion is ensured by one section having right-hand and the other left-hand helical teeth 40 cut at the same angle, the gear sections having teeth cut to correspond and the pinion as a unit having free end play, and therefore 45 being able to adjust itself and equalize the resultants of forces at the tooth contacts. The equality of the load along the length of the teeth in contact is ensured by 50 the property of restrained tipping of the frames supporting each pinion section; these frames do not touch the housing, and by virtue of the rocking base with which 55 each is provided in conjunction with the means employed to attach them to the bed of the reduction gear, each one is free to yield about the contact line of its base if

the load from any cause becomes uneven along the width of the tooth faces. The pinion is connected to turbine or other prime mover by the flexible shaft which 60 also runs through pinion sections, and by any suitable type of coupling which will permit longitudinal movement of shaft and pinion sections. The flexible shaft forms part of the construction in order that little 65 constraint shall be imposed on pinion sections or frames such as would prevent slight rocking of these frames on their bases.

By means of the construction outlined, when the device is in action, the separate 70 but flexibly connected pinion sections, both in their longitudinal position in frames and in the angular position of each of their axes are completely under the control of the forces of reaction transmitted by the teeth 75 of the large gear and give independent tooth bearing adjusting features to each pinion sleeve section. Also with the divided pinion the power is transmitted from flexible driving shaft to pinion sections by 80 means of coupling or key attachments at outer end of each. Therefore it is obvious that the stresses in each will be equal, and that distortion of pinion sections due to torsional stresses will be much less than 85 would be the case with a solid or one piece pinion having the power applied or delivered at one end; this small torsional error in pinion teeth is automatically taken care of by the before described construction, as 90 is also the torsion in that part of flexible driving shaft connecting the pinion sections together.

These and other details and objects of the invention are more fully described in the 95 following specification, set forth in the appended claims and illustrated in the accompanying drawings, wherein:

Figure 1 is a plan view of the device with cover removed. The bearing covers of rocking frames are not shown, and the divided pinion is shown in section. 100

Fig. 2 is a sectional elevation taken at A B (see Fig. 1). This view shows both rocking frames, the upper part of the one to the left being shown in vertical section along the centerline of the flexible driving shaft. 105

Fig. 3 is a sectional end view of the device taken at centerline C D (see Fig. 1).

Figure 4 is a fragmentary view in side 110 elevation, illustrating diagrammatically the sliding or flexible coupling.

- The mechanism as a whole is mounted on a bed or housing 1. The large gear is mounted in bearings 2, which form a part of the housing, by means of shaft extensions 3. 5 The shaft 3 is adapted to be connected by suitable means to the ship propeller shaft or other device which it is desired to drive from the high speed motor at a reduced speed of revolution.
- 10 The flexible shaft 4 is adapted to be driven by the high speed motor, such as a turbine, by means of the flexible or sliding coupling before mentioned; it may be termed the pinion shaft as with the pinion sleeve sections 5 and 6 and the connecting coupling 26 flanges 7 and 8, it forms this integral part of the device. The pinion shaft, through the medium of its pinion sleeve sections, is mounted in bearings 9 which 15 form a part of rocking frame 11, and in bearings 10 which form a part of rocking frame 12. The frames are mounted on suitable facings 13 and 14 which form a part of the bed or housing 1, and which are strongly 20 ribbed and supported in order to make them as rigid as practicable. The underside of the frame bases or the facings on which they are mounted are made with a cylindrical or beveled surface as shown by the drawing, 25 and these bases are a part of or solid with the lower part of the frames. The rocking frame bearing covers are indicated by 17 and 18.
- On each pinion section the teeth are cut at 30 opposite helical angles, the teeth 19 of the one meshing with the corresponding teeth of one section 21 of the large diameter gear, and the teeth 20 of the other meshing with the other gear section 22.
- 35 The shaft extensions 3, gear sections 21 and 22 and connecting drum 23 all form a rigid and rotatory gear wheel unit.
- The bases 15 and 16 of frames 11 and 12 are attached to the bed 1 by bolts 24 and 25. 40 The bolts 25 are holding down bolts which are fitted along lines of contact between cylindrical base faces 15 and 16 and facings 13 and 14; that is, along centerlines of bases 50 at right angles to shaft axes. The bolts 24 and 25 are intended to function as elastic connections to the bed 1 through this property of the steel of which they are made, and by this property to regulate and restrain any 55 rocking motion of the frames due to forces caused by misalignment the bolts 24 will have more movement to take care of than the bolts 25 and therefore they are made longer in order to provide the necessary amount of elasticity and are anchored in lower part 60 of bed, but as an alternative springs or spring washers may be used in conjunction with these bolts for effecting the same purpose, in either case they still retain their characteristic of elastic connections.
- 65 With further reference to the pinion shaft

it should be stated that the outer flange of coupling 7 is formed on and is part of the flexible shaft. The outer flange of coupling 8 is mounted and fixed on flexible shaft by suitable means; in the drawing it is shown 70 attached by means of a screw thread on shaft, and is made a fixture and part of the rotatory element by means of a key; this outer flange forms a means of adjustment for setting up the pinion teeth to the gear 75 teeth and should simplify the shop work when constructing the device.

It is to be noted that the large gear, including the sections 21 and 22 and the hollow sleeve pinion or divided pinion including the sections 5 and 6 constitute coacting gears.

What I claim as new is:

1. In transmission gearing, the combination of a rigid frame having bearings, a 85 shaft with gear wheels adapted to rotate in the bearings, movable frames adapted to rock on the rigid frame, bolts adapted to prevent lateral displacement of the movable frames, bolts adapted to resiliently restrain movement of the lateral frame, bearings on each movable frame, hollow pinions meshing with the gear wheel and mounted in the bearings of the movable frames, and the shaft extending through the pinions and 90 connected thereto.

2. In transmission gearing, the combination of a rigid frame, a shaft journalled in the same, helical gear wheels on the shaft, frames supported on rockers and carried by 100 the rigid frame, retaining bolts at the middle of the rockers, bolts at the ends of the rockers, a flexible shaft, sleeves journalled in the rocking frames and carried by the flexible shaft, and pinions on the sleeves and 105 meshing with the gear wheels.

3. In transmission gearing, the combination of a rigid frame, a shaft with gear wheels journalled in the same, rocking frames with bearings supported in the rigid 110 frame, bolts at opposite ends of the rockers, sleeves journalled in the bearings, a flexible shaft in the sleeves, flanges securing the ends of the sleeves to the shaft, and pinions on the sleeves and meshing with the 115 gear wheels.

4. A toothed-wheel gearing of the class described comprising driver pinions, bearing bodies for each driver pinion, a bearing box, a shaft for said driver pinions and means for mounting said bearing bodies within said bearing box so that they are adjustable relatively to each other along a plane passing through the axes of said 120 driver pinions.

5. A toothed-wheel gearing comprising driver pinions, spur wheels meshing with said driver pinions, a bearing body in which each driving pinion is mounted, a bearing box, supporting ribs formed on said bearing 130

box and means formed on said bearing bodies and cooperating with said supporting ribs for supporting said bearing bodies so that they may adjust themselves relatively to each other along a plane passing through the axes of said driver pinions.

6. A toothed-wheel gearing comprising a pair of driver pinions, a shaft for said pinions, said shaft being of comparatively small diameter, means connecting said shaft to said pinions at the outer ends of said pin-

ions thereby allowing a clearance between said pinions and said shaft throughout the remainder of said pinions, bearing bodies provided for each of said pinions, a bearing box and means for supporting said bearing bodies within said bearing box whereby they may adjust themselves relatively to each other along a plane passing through the axes of said pinions.

10 In testimony whereof I affix my signature.

CHARLES F. CLAPHAM.
